UNITED STATES PATENT OFFICE.

GEORGES BAILLOT, OF EMBOURG, NEAR LIEGE, BELGIUM.

FOUR-CYLINDER COMPOUND LOCOMOTIVE.

Application filed June 17, 1920. Serial No. 389,692.

To all whom it may concern:

Be it known that I, GEORGES BAILLOT, a subject of the King of Belgium, residing in Embourg, near Liege, in Belgium, 5 have invented certain new and useful Improvements in Four-Cylinder Compound Locomotives, of which the following is a specification.

The object of this invention is to improve 10 the construction of four-cylinder compound locomotives.

One of the features of this invention consists in the fact that the propelling mechanisms are disposed in pairs in order to obtain 15 a perfect balance and to avoid the disadvantages arising from the tendency to bind or lock on a dead center at 180°, i. e. that the outside or high pressure cylinders, being horizontal, and the inside or low pressure 20 cylinders, being inclined at 7°, relative to the outside or high pressure cylinders every group or pair may be controlled by only one horizontal main slide valve, and also that the driving rods all acting upon 25 the second coupled axle, are coupled in pairs in such a manner that one small and one large piston, on the same side of the engine, are always moving together in the same direction.

30 Another feature, is that the front bearer axle or pilot-truck axle receives the load imparted to it, through floating levers connected with a balanced cross-spring.

A further feature still, is that the outer 35 cranks being set accurately, with their respective wheels, the steam admission to the small pistons is always in advance of that to the expansion cylinders; and also, that unequal values, are imparted to the distributing motions of the slide-valves, this allowing of attaining, in a very simple way, the advantages in working generally aimed at in double expansion locomotives.

Another feature is that, in the starting, 45 the feeding of live steam is insured by a cock located in the middle of every small cylinder and which may produce an excess of admission on reaching even to the anticipated escape.

50 Another feature consists in the disposition under the steam chests, of two longitudinal cocks, with generalized action and driven by a servo-motor or automatically controlled motor; said cocks being arranged so that 55 they may open all the ports at once to the

free air and serve simultaneously as drain valves, by-pass and snifters.

Another feature is that the small crank arms in the first coupled axle, insures the free motion of the internal driving rods, 60 whatever be their length and the degree of proximity between this axle and the driving axle.

In the accompanying drawings, given as example of one form of construction of the 65 invention; Fig. 1 is a general elevation view of the locomotive; Fig. 2 is a vertical transverse section through the front end of the locomotive at the steam inlet port of the high pressure cylinder; Fig. 3 is a part of 70 a longitudinal section, and Fig. 4 is a horizontal section mainly along the plane of axles, Figs. 3 and 4 being on the same scale as Fig. 2.

The locomotive as a whole comprises a 75 frame and a truck of six or eight coupled wheels AAAA, the second pairs of wheels being coupled to cranked axles F, and in the front a smaller truck or pilot-truck B (Fig. 1). When necessary a rear or trailer 80 truck may be provided under the firebox. The front or pilot-truck is allowed a certain lateral play and partakes in the suspension through a balanced cross-spring T (Figs. 2 and 3), supported at the middle by 85 the frame of the locomotive and at the ends by inwardly inclined brackets 12 secured to bearings on the interior sides of the wheels of the truck. The shouldering under the box of cylinders, receives the corresponding load through the levers SS each rocking at one end thereof on the upper part of the axle-boxes (Figs. 3 and 4), and having at the other end thereof an apertured head 10 which loosely engages on 90 pin 11 mounted on the frame of the locomotive. The inclination of the spring suspension rods 12 which are secured at their upper ends to the bearings on the inner side of the pilot truck wheels and passing 100 through the outer ends of the spring T have at their lower ends the nuts 13 under the springs, Figs. 2 and 3, in cooperation with the action of the spring buffers 12', Fig. 1, working on the axle box guides, always 105 tends to bring the locomotive in the middle of the track in the event of head on contact thereof with another object.

The rigid wheel-base will always be the most resisting base of a locomotive, and the 110

overhang, in the modern engines is not as great as formerly, and is so much less in the present device that it permits of greatly lessening the uneven movement of the 5 spring $\ddot{T}$.

In the front, the four cylinders are in transverse alinement and do not project beyond the small front or pilot-truck more than is strictly necessary (Figs. 1 and 4).

- 10 The external or high pressure cylinders C, C are horizontal, whilst the internal or low pressure cylinders D, D are inclined at 7°. Each pair of one large and one small cylinder, is governed by only one horizontal slide 15 valve I, which is located in a steam chest I', located under the large cylinder (Figs 3 and 4).

The connecting or driving rods E, E, E', E', work all on the second coupled axle F 20 (Figs. 1, 3 and 4) and are coupled in pairs, so that one large piston D' and one small piston C' on the same side of the engine, move always together in the same direction. Short connecting or driving rods E² are secured to first and second pairs of driving 25 wheels exteriorly of the driving wheels and interiorly of the connecting or driving rods E, and timed to move in unison with the driving rods E, and E' of each side of the locomotive.

The block comprising the four cylinders is preferably cast of one piece.

Owing to the possibility due to the use of 30 coupled wheels of moderate diameter, to condense the several organs of the mechanism, whilst reducing the unitary pressures on same, it has been possible to effect the suspension of the second and third axles by 35 springs V (Fig. 3) located inside the frame of the locomotive and directly above the axle-boxes, this affording an increase of stability.

It may be seen from the foregoing that in 40 every pair of two cylinders, the outer high-pressure driving pins G, being set accurately with their corresponding low-pressure crank arms H, the action of the four driving rods will be uniformly distributed against all 45 the fulcrums afforded by the bearing of the axle-boxes (Fig. 4).

As far as the balancing of the parts receiving an alternating motion is concerned, it will be adequate to have the low-pressure 50 pistons made of aluminum. Moreover, the four driving rods acting in pairs on the same will be therewith regulated, to counterbalance the high-pressure pistons against the resistance at the end of stroke, produced on said parts by the compression and pre-admission.

The single slide-valve I in the steam chest I' controlling at the same time one large and one small cylinder are driven by inverted Walschaerts link motions K, the 60 front parts of which are acted upon by the

rods 16, of eccentrics N located on the first coupled axle (Fig. 3).

The eccentric discs N' of the two distributions are forged and turned with the small crank arms O which crank arms are 70 arranged in the axle of the front drivers AA, for the free play of the interior low-pressure rods, (Figs. 3 and 4).

In view of the arrangement of the steam-chest under the large or low pressure cylinders, the mechanism L of every valve motion is located between its low-pressure driving rod and the longitudinal beam of the frame of the locomotive, (Fig. 4). The free passage arranged in the middle of the 80 engine, and so strikingly illustrated in the plan view, insures the accessibility of the mechanism under the best of conditions.

As soon as a crank arm O has reached its dead-point its eccentric is accurately perpendicular to the horizontal or traction line of the slide-valves.

The low-pressure pistons and cylinders D, D' inclined at 7°, act upon the valve-motion (Figs. 3 and 4). The outer high-pressure cranks G being set accurately with their respective arms H, it is obvious that, for the forward stroke, the control of the valve-motion on the small pistons will always be in advance of 7° on those of the low-pressure cylinders, since the high-pressure pistons are retarding at the same rate against the internal mechanisms.

The laps provided for high pressure admission, being equal 32 mm.—i. e. one half 100 of the total dead stroke of the slide-valves (slide-blocks at the dead point) and the low-pressure laps being 28 mm. each, the linear advance, which is null at high-pressure, will result, for forward stroke, in an immutable 105 angular advance of 7°, whatever may be the amount of the admission.

Beyond this feature of the steady high-pressure angular advance, the valve motion affords automatically, and in inversely proportional limits, an average elongation of 25 per cent of the low pressure admission as 110 against the high-pressure admission, a slight diminution of the high-pressure compression with corresponding increase of 115 exhaust and last, admittance opening, at the high-pressure ports, much quicker and larger than those obtained with the ordinary means of the Walschaerts slide gear.

The high-pressure admission, in practice, 120 is obviously less than the maximum low-pressure admission. This affords no difficulty at the starting, owing to the steam feeding insured by means of cocks P, provided in the middle of each small cylinder, 125 (Figs. 1 and 2).

For backward run, the same features in the operation of valve-motion will be reproduced although attenuated, it should be however, that a retardation of 7° occurs in 130

the high-pressure admission, corresponding with the steady angular advance mentioned above, this however, can have no inconvenience with the compound working.

5 The slide-valve I of the hollow-type having the four partitions 14 admits in its middle port 15 the live-steam which is simultaneously received in first emission and contained in second expansion between the extreme partitions through the external edges of which takes place the final exhaust (Figs. 3 and 4). Owing to this device, the pressure from the steam chest (the feeding of which is always insured by at least one of said cocks P) can only act either as back pressure or as compression, after an auxiliary admission or excess of admission under high-pressure however slow might be the speed of running.

20 With this very simple device, the maximum live-power at the starting, is lower than the energy produced in the most favorable position by a compound locomotive working with four directly fed cylinders; on the other hand, the minimum of power is larger by at least 30 per cent, this producing in every position a propulsion adequate to the possibilities of the occasion.

30 Alone, the compression-relieving valves provided on the bottom of the low-pressure cylinders, limit the intermediate pressure. With the relief cocks P P, supposed to be of very small section, the setting under pressure of the steam chest and of the low-pressure cylinders, is only considered at the starting, as subsidiary since, a high but gradually reached motive-momentum hinders effectively any undue slipping of the wheels.

40 The internal low pressure mechanisms are balanced through a counter-weight Q, with short lever arm q, serving for both crank arms, which obviates any increase of wear of the track, under the action of the adjacent driving wheels (Fig. 3).

50 Last of all, two elongated longitudinal cocks or air distributors R R (Fig. 2) with generalized action and driven by servo-motors or automatically controlled motors are provided in the bosses that form cock-bodies under the slide-valve boxes. These distributors may open simultaneously all the ports, (even that of the steam chest) to the free air during the running with closed controller (Figs. 2 and 3).

Having thus described my invention, what I claim as new and desire to secure by Letters-Patent is:

60 1. In a multiple cylinder locomotive the combination of, high pressure cylinders; and low pressure cylinders; the low pressure cylinders being inclined relative to the high pressure cylinders.

65 2. In a multiple cylinder locomotive the

combination of, high pressure cylinders; and low pressure cylinders, the low pressure cylinders being inclined at seven degrees relative to the high pressure cylinders.

3. In a multiple cylinder locomotive the combination of, high pressure cylinders; and low pressure cylinders; the cylinders being arranged in pairs comprising a high pressure cylinder and a low pressure cylinder, and the low pressure cylinders being inclined relative to the high pressure cylinders.

4. In a multiple cylinder locomotive the combination of, high pressure cylinders; and low pressure cylinders; the cylinders being arranged in pairs comprising a high pressure cylinder and a low pressure cylinder, and the low pressure cylinders being inclined at seven degrees relative to the high pressure cylinders.

5. In a multiple cylinder locomotive the combination of, horizontal high pressure cylinders; and low pressure cylinders, the low pressure cylinders being inclined relative to the high pressure cylinders.

6. In a multiple cylinder locomotive the combination of, horizontal high pressure cylinders; and low pressure cylinders, the low pressure cylinders being inclined at seven degrees relative to the high pressure cylinders.

7. In a multiple cylinder locomotive the combination of, horizontal high pressure cylinders; and low pressure cylinders, the cylinders being arranged in pairs comprising a high pressure cylinder and a low pressure cylinder, and the low pressure cylinders being inclined relative to the high pressure cylinders.

8. In a multiple cylinder locomotive the combination of, horizontal high pressure cylinders; and low pressure cylinders; the cylinders being arranged in pairs comprising a high pressure cylinder and a low pressure cylinder, and the low pressure cylinders being inclined at seven degrees relative to the high pressure cylinders.

9. In a multiple cylinder locomotive the combination of, high pressure cylinders; low pressure cylinders; the cylinders being arranged in pairs comprising a high pressure cylinder and a low pressure cylinder, the low pressure cylinder of each pair being inclined relative to the high pressure cylinders; and a single valve for controlling each pair of cylinders.

10. In a multiple cylinder locomotive the combination of, high pressure cylinders; low pressure cylinders; the cylinders being arranged in pairs comprising a high pressure cylinder and a low pressure cylinder, the low pressure cylinders being inclined relative to the high pressure cylinders; and a single slide valve for controlling each pair of cylinders.

11. In a multiple cylinder locomotive the combination of, high pressure cylinders; low pressure cylinders; the cylinders being arranged in pairs comprising a high pressure cylinder and a low pressure cylinder, the low pressure cylinder being inclined relative to the high pressure cylinder; and a single horizontal slide valve for controlling each pair of cylinders.
12. In a multiple cylinder locomotive the combination of, high pressure cylinders; low pressure cylinders; the cylinders being arranged in pairs, each pair comprising a high pressure cylinder and a low pressure cylinder, the low pressure cylinders of each pair being inclined relative to the high pressure cylinders; and a single valve for controlling each pair of cylinders.
13. In a multiple cylinder locomotive the combination of, high pressure cylinders; low pressure cylinders; the cylinders being arranged in pairs, each pair comprising a high pressure cylinder and a low pressure cylinder, the low pressure cylinder of each pair being inclined relative to the high pressure cylinder; and a single slide valve for controlling each pair of cylinders.
14. In a multiple cylinder locomotive the combination of, horizontal high pressure cylinders; low pressure cylinders; the cylinders being arranged in pairs comprising a high pressure cylinder and a low pressure cylinder, the low pressure cylinders being inclined relative to the high pressure cylinders; and a single slide valve for controlling each pair of cylinders.
15. In a multiple cylinder locomotive the combination of, horizontal high pressure cylinders; low pressure cylinders; the cylinders being arranged in pairs comprising a high pressure cylinder and a low pressure cylinder, the low pressure cylinders being inclined relative to the high pressure cylinders; and a single horizontal slide valve for controlling each pair of cylinders.
16. In a multiple cylinder locomotive the combination of, high pressure cylinders; low pressure cylinders; the cylinders being arranged in pairs comprising a high pressure cylinder and a low pressure cylinder, the low pressure cylinder of each pair being inclined relative to the high pressure cylinder; a steam chest between each pair of cylinders and a single slide valve for each steam chest for controlling each pair of cylinders.
17. In a multiple cylinder locomotive the combination of, horizontal high pressure cylinders; low pressure cylinders; the cylinders being arranged in pairs comprising a high pressure cylinder and a low pressure cylinder; and the low pressure cylinder of each pair being inclined relative to the high pressure cylinder; a steam chest between each pair of cylinders; and a single horizontal slide valve for each steam chest for controlling each pair of cylinders.
18. In a multiple cylinder locomotive the combination of, high pressure cylinders; low pressure cylinders; the cylinders being arranged in pairs, each pair comprising a high pressure cylinder and a low pressure cylinder, the low pressure cylinder being inclined relative to the high pressure cylinder; a steam chest between each pair of cylinders; a single slide valve for each steam chest for controlling each pair of cylinders; and link and eccentric means for operating each slide valve.
19. In a multiple cylinder locomotive the combination of, horizontal high pressure cylinders; low pressure cylinders; the cylinders being arranged in pairs, each pair comprising a high pressure cylinder and a low pressure cylinder, the low pressure cylinder being inclined relative to the high pressure cylinder; a steam chest between each pair of cylinders; a single horizontal slide valve for each steam chest for controlling each pair of cylinders; and link and eccentric means for operating each slide valve.
20. In a multiple cylinder locomotive the combination of, high pressure cylinders; low pressure cylinders; the cylinders being arranged in pairs, each pair comprising a high pressure cylinder and a low pressure cylinder; the low pressure cylinders being inclined relative to the high pressure cylinders; a steam chest between each pair of cylinders; a single slide valve for each steam chest; and dependent link and eccentric means for operating each slide valve.
21. In a multiple cylinder locomotive the combination of, horizontal high pressure cylinders; low pressure cylinders; the cylinders being arranged in pairs comprising a high pressure cylinder and a low pressure cylinder; the low pressure cylinders being inclined relative to the high pressure cylinders; a steam chest between each pair of cylinders; a single slide valve for each steam chest; and dependent link and eccentric means for operating each slide valve.
22. In a multiple cylinder locomotive the combination of, high pressure cylinders; low pressure cylinders; the cylinders being arranged in pairs comprising a high pressure cylinder and a low pressure cylinder, the low pressure cylinders being inclined relative to the high pressure cylinders; a steam chest between each pair of cylinders; a horizontal slide valve for each steam chest for controlling each pair of cylinders; means for operating such slide valve; a first pair of driving wheels coupled on the outer ends of a cranked axle; rods connecting the pistons of the high pressure cylinders and the exterior sides of the second pair of driving wheels; and rods connecting the pistons of the low

pressure cylinders and said cranked axle; the connecting rods of each pair of cylinders being movable in unison.

23. In a multiple cylinder locomotive the combination of, high pressure cylinders; low pressure cylinders; the cylinders being arranged in pairs comprising a high pressure cylinder and a low pressure cylinder and the low pressure cylinders being inclined relative to the high pressure cylinders; a steam chest between each pair of cylinders; a horizontal slide valve for each steam chest for controlling each pair of cylinders; a first pair of driving wheels coupled on a straight axle; a second pair of driving wheels coupled on the outer ends of a cranked axle; rods connecting the pistons of the high pressure cylinders and the exterior sides of the second pair of driving wheels; rods connecting the pistons of the low pressure cylinders and said cranked axle; and rods connecting the first and second pairs of driving wheels on the exterior sides of the wheels intermediate of the exterior of said wheels and the connecting rods of the admission cylinders; all of said connecting rods on each side of the locomotive being movable in unison. 70

24. In a multiple cylinder locomotive the combination of, high pressure cylinders; low pressure cylinders; the cylinders being arranged in pairs comprising a high pressure cylinder and a low pressure cylinder; the low pressure cylinder being arranged at an incline relative to the high pressure cylinder; a first pair of driving wheels coupled on a straight axle; a second pair of driving wheels coupled on the outer ends of a cranked axle; a counterweight for the cranked axle; a lever arm for the counterweight; rods connecting the pistons of the high pressure cylinders and the exterior sides of the second pair of driving wheels; and rods connecting the pistons of the low pressure cylinders and said cranked axle; the connecting rods of each pair of cylinders being movable in unison. 85

25. In a locomotive the combination of, a frame for the locomotive; and a pilot truck comprising wheels coupled on an axle, a spring parallel to said axle suspended on the frame of the locomotive adjacent to the middle of said axle, and inwardly inclined dependent rods converging towards their lower ends secured at their upper ends to the bearings of said wheels on the inner sides thereof, the lower ends of said rods passing through the outer ends of said spring and being secured thereto for supporting said outer ends and permitting movement of said outer ends on said rods for relieving the strain of the weight imposed on said wheels. 100

26. In a locomotive the combination of, a frame of the locomotive; and a pilot truck comprising wheels coupled on an axle, 115

a spring parallel to said axle suspended on the frame of the locomotive adjacent to the middle of said axle, inwardly inclined dependent rods secured at their upper ends to the bearings of said wheels on the inner sides thereof, the lower ends of said rods passing through the outer ends of said spring and permitting movement of said outer ends on said rods and nuts for the lower ends of said brackets on the under side of said spring. 75

27. In a locomotive the combination of, a frame of the locomotive; a pilot truck comprising wheels coupled on an axle, boxes for said axle, a spring parallel to said axle suspended on the frame of the locomotive adjacent to the middle of said axle, inwardly inclined dependent rods secured at their upper ends to the bearings of said wheels on the inner sides thereof, the lower ends of said rods passing through the outer ends of said spring and permitting movement of said outer ends on said brackets, nuts for the lower ends of said rods on the under side of said spring; and lever arms, the lever arms at one of their ends rocking on the boxes of said axle and at the other of their ends being movably connected to said frame of the locomotive. 80

28. In a multiple cylinder locomotive the combination of, high pressure cylinders; low pressure cylinders; the cylinders being arranged in pairs comprising a high pressure cylinder and a low pressure cylinder; a single valve for controlling each pair of cylinders; and means appurtenant to each of the high pressure cylinders for feeding additional live steam thereto at starting. 95

29. In a multiple cylinder locomotive the combination of, high pressure cylinders; low pressure cylinders; the cylinders being arranged in pairs comprising a high pressure cylinder and a low pressure cylinder; a single valve for controlling each pair of cylinders; and means located substantially midway longitudinally of each of the high pressure cylinders at the top thereof for feeding additional live steam thereto at starting. 100

30. In a multiple cylinder locomotive the combination of, high pressure cylinders; low pressure cylinders; the cylinders being arranged in pairs comprising a high pressure cylinder and a low pressure cylinder, the low pressure cylinder of each pair being inclined relative to the high pressure cylinder; a single valve for controlling each pair of cylinders; and means appurtenant to each of the high pressure cylinders for feeding additional live steam thereto at starting. 115

31. In a multiple cylinder locomotive the combination of, high pressure cylinders; low pressure cylinders; the cylinders being arranged in pairs comprising a high pressure cylinder and a low pressure cylinder, 120

the low pressure cylinder of each pair being inclined relative to the high pressure cylinder; a single slide valve for controlling each pair of cylinders; and means located substantially midway of each of the high pressure cylinders at the top thereof for feeding additional live steam thereto at starting.

32. In a multiple cylinder locomotive the combination of, low pressure cylinders; high pressure cylinders; the cylinders being arranged in pairs comprising a high pressure cylinder and a low pressure cylinder; a steam chest between each pair of cylinders; valve means for controlling each pair of cylinders; and means operated by a motor for simultaneously opening all the ports of the valve means of each pair of cylinders to free air and serving as drain valves, bypass and sniffers.

33. In a multiple cylinder locomotive the combination of, low pressure cylinders; high pressure cylinders; the cylinders being arranged in pairs comprising a high pressure cylinder and a low pressure cylinder; a steam chest between each pair of cylinders; valve means for controlling each pair of cylinders; and means operated by a motor for simultaneously opening all the ports of the valve means and of the steam chest of each pair of cylinders to free air and serving as drain valves, bypass and sniffers.

34. In a multiple cylinder locomotive the combination of, high pressure cylinders; low pressure cylinders; the cylinders being arranged in pairs comprising a high pressure cylinder and a low pressure cylinder, the low pressure cylinder of each pair being inclined relative to the high pressure cylinder; a steam chest between the cylinders of each pair; valve means for controlling each pair of cylinders; and means operated by an automatically controlled motor

for simultaneously opening all the ports of the valve means of each pair of cylinders to free air and serving as drain valves, bypass and sniffers.

35. In a multiple cylinder locomotive the combination of, high pressure cylinders; low pressure cylinders; the cylinders being arranged in pairs comprising a high pressure cylinder and a low pressure cylinder, the low pressure cylinder of each pair being inclined relative to the high pressure cylinder; a steam chest between the cylinders of each pair; valve means for controlling each pair of cylinders; and means operated by an automatically controlled motor for simultaneously opening all the ports of the valve means and of the steam chest of each pair of cylinders to free air and serving as drain valves, bypass and sniffers.

36. In a locomotive the combination of, a frame of the locomotive; a pilot truck comprising wheels coupled on an axle, a spring parallel to said axle suspended on the frame of the locomotive adjacent to the middle of said axle, inwardly inclined dependent rods secured at their upper ends to the bearings of said wheels on the inner sides thereof, the lower ends of said rods passing through the outer ends of said spring, and nuts for the lower ends of said rods on the under side of said spring; and buffers on the front of the locomotive cooperating with said rods whereby upon contact of the buffers with an object the tendency is to bring the locomotive in the middle of the track.

In testimony whereof, I have hereunder affixed my signature in presence of the two witnesses.

GEORGES BAILLOT.
